ARTICLE OF JEWELRY

Louis Garfinkel, Providence, R. I., assignor to
T & R Jewelry Co., Providence, R. I., a corporation of Rhode Island

Application July 23, 1936, Serial No. 92,168

7 Claims. (Cl. 63—1)

The present invention relates to an article of jewelry and more particularly to a combination bar-pin and clip-brooch.

One object of the present invention is to provide an article of the type indicated comprising a plurality of ornaments adapted to be interchangeably mounted on either a bar-pin or a hinged clip.

Another object of the invention is to provide interchangeable ornaments adapted to be attached to the supporting member of a bar-pin or a hinged clip and yieldingly latched in position thereon.

Another object of the invention is to provide an article of the type indicated in which interengaging parts of the ornament and bar-pin or clip may be economically manufactured as sheet-metal stampings.

Another object of the invention is to provide an article of the type indicated having a simple and compact structure of highly ornamental appearance, and one in which the ornaments are adapted to be easily and quickly assembled on either the bar-pin or clip.

Further objects of the invention are set forth in the following specification which describes a preferred form of construction of the article, by way of example, as illustrated by the accompanying drawing. In the drawing:

Fig. 1 is a plan view of the bar-pin embodying a pair of ornaments mounted in juxtaposition on a supporting member;

Fig. 2 is a rear view of the bar-pin showing the means for attaching the ornaments to the supporting member;

Fig. 3 is a longitudinal sectional view on line 3—3 of Fig. 2 showing the interengaging means for yieldingly holding the ornaments against movement longitudinally of the supporting member;

Fig. 4 is a longitudinal sectional view similar to Fig. 3 showing the yielding detent at the end of the supporting member seated in a recess in the ornament to aline the parts prior to sliding the ornament into position;

Fig. 5 is a transverse sectional view on line 5—5 of Fig. 2 showing the spaced channels on the ornament embracing the sides of the supporting member;

Fig. 6 is a perspective view of the bar-pin and one of the ornaments in disassembled alined relationship;

Fig. 7 is a perspective view of a modified form of supporting member for mounting a plurality of ornaments;

Fig. 8 is a perspective view of a clip-brooch with an interchangeable ornament mounted thereon; and

Fig. 9 is a transverse sectional view of the clip-brooch showing the ornament positioned on one of the leaves of the clip prior to sliding it into position thereon.

Referring to the drawing, the bar-pin is herein illustrated as comprising an ornament-supporting member in the form of a flat plate 10 having ears 11 at one end for hingedly mounting a pin-stem 12 and a keeper 13 at its opposite end provided with a safety catch 14. The plate 10 is preferably stamped from sheet-metal stock to form a widened central portion 15 and narrower rectangular wings 16 extending therefrom with shoulders 17 therebetween. During the stamping operation intermediate portions of the plate are preferably punched out or perforated to lighten its weight and save stock. The end perforations 18 are of horseshoe shape to provide longitudinally-extending tongues 19. The ends of the tongues 19 are indented during the stamping operation, or by a separate operation, to form shallow cavities or recesses on one side and ball-shaped protuberances 20 on the opposite side which act as detents for the ornaments applied to the pin. Preferably, a transverse crossbar 21 extends across the perforated central portion of the plate for a purpose as will later appear.

The interchangeable ornaments 24 may take any desired form of configuration, being herein illustrated as comprising an ornamental setting for brilliants, jewels or the like provided with a guideway 25 on its rearward face adapted to slide over the wings 16 of the supporting member 10 of the bar-pin. The guideway may be formed by slotting the material of the ornament or in any other suitable manner; being herein illustrated as comprising a plate 26 soldered or otherwise attached to the back of the ornament. The plate 26 has side extensions folded around to form spaced channels 27 which terminate short of one end of the plate to provide a narrower extension or lip 28. An elongated recess 29 is formed in the extending lip 28 and a circular recess 30 provided at the opposite end of the plate 26 for seating the detent 20 on the supporting member 10 of the pin. The elongated recess 29 has an inclined or sloping bottom, as shown in Fig. 6, for a purpose as later explained.

The ornament 24 may be mounted on one of the wings 16 of the supporting member 10 of the bar-pin by first placing the detent 20 on the resilient tongue 19 in the recess 29 on the plate 55

26 as illustrated in Fig. 4. The opposite sides of the wings 16 will then be alined with the grooves in the channels 27 so that the ornament may be bodily slid longitudinally of the member or plate 10. During this relative sliding movement of the parts the resilient tongue 19 yields to allow its detent protuberance 20 to ride up the incline in the bottom of the recess 29 as the edges of the member 10 are engaged in the 10 grooves of the channels 27. In this manner the detent 20 guides the member 10 into register with the grooves and finally the ends of the channels 27 engage the shoulders 17 as the detent 20 snaps into the recess 30 in the plate 26. The 15 detent 20 and recess 30 thus form interengaging means for yieldingly latching the ornament against movement longitudinally of the bar-pin. Another ornament 24 of the same type may be slid over the opposite wing 16 of the member 10 20 in the manner as explained and into juxtaposition with respect to the first ornament to form an assembled brooch as illustrated in Fig. 1. The central crossbar 21 of the member 10 then covers the joint between the abutting edges of 25 the two ornaments to prevent light from showing through, thus giving the article a finished appearance. Each ornament may be detached from the bar-pin by merely sliding it outwardly longitudinally of the wing 16 on which it is 30 mounted. At the beginning of the outward movement of the ornament the resilient tongue 19 of the member 10 yields to permit the rounded detent 20 to slide out of the recess 30 and then along the center of the plate 26 until the ornament 35 is wholly detached.

A modified form of bar-pin or brooch is illustrated in Fig. 7 for mounting a cluster of ornaments. The plate 35 of this form of the article has a square central portion 36 with wings 39 extending at right-angles to each other to form 40 a cross. Each of the wings has a horseshoe shaped slot 18 adjacent its end, as explained with respect to the plate 10, to form a resilient tongue 19 and the plate is adapted to mount ornaments 45 of any suitable contour preferably having pointed ends which dovetail together as indicated in Fig. 7.

Figs. 8 and 9 illustrate a clip 40 which is adapted to mount one of the interchangeable ornaments described above. The clip 40 is of usual 50 construction comprising a pair of leaves 41 and 42 hinged together by the pivot-pin 43. The leaf 41 is provided with projecting prongs 44 for gripping an article of clothing and a spring-finger 45 for resiliently holding it in either open 55 or closed position with respect to the leaf 42. The leaf 42 is of a construction similar to the wings 16 of the supporting member 10 of the bar-pin previously described, having a resilient tongue 19 provided with a convex detent 20 at its end.

When it is desired to apply one of the ornaments 24 to the clip-brooch it is detached from the plate 10 of the bar-pin and mounted on the leaf 42 of the clip in the manner as previously 60 explained. To this end the detent 20 at the end of the resilient tongue 19 on the leaf 42 of the clip is placed in the recess 29 in the plate 26 of the ornament to aline the side edges of the leaf with the grooves formed by the channels 27. The 65 ornament is then slid longitudinally of the leaf 42 until the detent 20 snaps into the recess 30 to yieldingly hold the ornament in place on the clip. With the leaf 41 in the position illustrated in full lines in Fig. 9 the clip may be attached 70

to an article of clothing by pressing the two leaves together in the manner indicated by dash lines. The spring-finger 45 acting against a suitable abutment on the hinge causes the leaf 41 to snap into closed position with respect to the leaf 42 to grip the prongs 44 against the article of clothing. 5

A preferred form of the article having now been described in detail it will be understood that various modifications may be made in the structure and arrangement of its parts within the scope of the invention. For example, the channeled plate may be on the bar-pin or clip for cooperation with a rectangular plate on the ornament, and the resilient latching tongue may be 15 on the ornament for cooperation with a recess in the bar-pin or clip. Further, the resilient tongue may be a separate element attached to the plate instead of being integrally formed as 20 illustrated.

It will now be observed from the foregoing that the invention provides a novel form of combined bar-pin and clip-brooch in which a single or a plurality of ornaments may be used with either a bar-pin or a clip. It will also be observed that 25 the novel construction of the ornament provides for its convenient attachment to and detachment from the supporting member on the bar-pin or clip. Still further, it will be observed that the novel combination brooch provides for 30 slidably mounting the interchangeable ornaments on either a bar-pin or a clip and yieldingly holding the ornaments from movement relatively thereof.

While the invention is herein described and 35 illustrated as embodied in a preferred form of construction, it is to be understood that modifications may be made in the design and arrangement of its parts without departing from the spirit or scope of the invention. Therefore, 40 without limiting myself in this respect, I claim:

1. An article of jewelry comprising a supporting member, an ornament having spaced channels forming a guideway, said member being slidable in the guideway between the channels to mount 45 the ornament on the member, a resilient tongue on one of the parts provided with a detent at its free end, and said other part having a recess engaged by the detent to hold the ornament in position on the member, said tongue and recess being 50 positioned between the channels and said tongue being movable at an angle to the plane of the part on which it is carried.

2. An article of jewelry comprising a supporting member, an ornament having a plate with the 55 edge portions thereof folded around to form spaced channels for slidably mounting the ornament on the supporting member, a resilient tongue on the supporting member having a detent at its end, said tongue being positioned between the 60 sides of the supporting member and said detent projecting at right-angles to the plane thereof, and said plate on the ornament having a recess positioned between the channels and adapted to be engaged by the detent for yieldably holding the 65 parts in assembled relationship.

3. An article of jewelry comprising a supporting plate with a cut-out portion forming a centrally-positioned resilient tongue with its free end adjacent the end of the plate, a detent at the end 70 of the tongue, an ornament having a plate with its edge portions folded around to form spaced channels and provided with a recess between the channels, said channeled plate being slidable on the supporting plate to mount the ornament and said 75

detent cooperating with the recess to yieldingly hold the ornament in position on the supporting plate.

4. An article of jewelry comprising a supporting plate apertured to form centrally-positioned resilient tongues extending in opposite directions with their free ends adjacent the opposite ends of the plate, detents on the free ends of the tongues, ornaments adapted to be slidably mounted in juxtaposition on the supporting plate to form a brooch, said ornaments having spaced channels for embracing the sides of the supporting plate and forming a guideway therebetween, and said ornaments having recesses at the opposite ends of the guideways between the channels for receiving the detents on the tongues of the supporting plate.

5. An article of jewelry comprising a supporting member, an ornament having a guideway, said supporting member being slidable in the guideway on the ornament, interengaging means positioned centrally of the supporting member and ornament including a recess on one part and a resilient tongue on the other part having a detent projecting outwardly at right-angles to the plane thereof, said interengaging means detachably holding the parts in assembled relationship, and a beveled recess on one part for initially receiving the detent on the other part to adapt the

supporting member to be aligned with the guideway on the ornament.

6. An article of jewelry comprising a supporting member having a resilient tongue intermediate its sides and projecting from the plane thereof, said tongue having a detent at its free end, an ornament having a guideway with spaced channels for slidably receiving the supporting member, a recess in the guideway between the channels for seating the detent on the tongue of the supporting member to detachably hold the parts in assembled relationship, and an inclined recess on the ornament positioned forwardly of the spaced channels for seating the detent on the supporting member to align the latter with the spaced channels and to permit the ornament to be easily slid into position on the supporting member.

7. A clip-brooch comprising a pair of hinged leaves, one of said leaves being apertured to form a resilient tongue, a detent at the free end of the tongue, prongs on the opposite leaf adapted to cooperate with the apertured leaf to grip an article of clothing, and an ornament having a guideway with spaced channels for receiving the apertured leaf, and a recess in the guideway between the channels for seating the detent on the tongue to detachably hold the parts in assembled relationship.

LOUIS GARFINKEL. 30
